SNOW FENCING

George Lionel Rodolphe Longtin, St. Johns, Quebec, Canada, assignor to Kraft Paper Products Limited, St. Johns, Quebec, Canada

Application March 10, 1950, Serial No. 148,921

2 Claims. (Cl. 139—425)

1

This invention relates to improvements in fences and more particularly to fencing strips used in erecting fences to serve as a snow drifting barrier or the like.

A particular object is to provide a fencing strip of twisted strands of paper woven together to form an open mesh paper fence with a novel reinforced selavage portion at or near the top and bottom of the fencing strip to prevent sagging and curling of the strip sections between adjacent supporting posts.

Another object is to provide spaced intermediate stiffened zones throughout the fencing strip to form an adequate engaging surface for suitable fastening elements employed for securing the fencing strip to the posts.

A particular feature of these stiffened zones is that, in addition to affording an engaging surface for the fastening elements at any desired point throughout the length of the strip, they serve to stiffen the fence between posts along spaced narrow zones paralleling the top and bottom of the fence.

Another feature is in the provision of woven twisted strands of paper which are treated with a waterproofing compound and fungicide, rendering the fencing impervious to deterioration by weathering or fungus rot.

The above and other objects and features characteristic of this invention will be understood more readily from the following detailed description taken in connection with the accompanying drawings, in which—

Fig. 1 is a perspective view showing a fencing embodying my invention as it would appear on a line of posts.

Fig. 2 is an enlarged fragmentary view of the fencing in Fig. 1, showing the selavage portion secured to a post.

Fig. 3 is an enlarged fragmentary view showing an intermediate portion secured to a post.

Fig. 4 is a fragmentary view in perspective showing the reverse side of the selavage portion with a fastening element trained therethrough.

Fig. 5 is a sectional view, enlarged, taken along the lines 5—5 of Fig. 2.

Fig. 6 is a sectional view, enlarged, taken along lines 6—6 of Fig. 3.

Referring more particularly to the drawings, Fig. 1 generally depicts a snow fencing 5 secured to conventional upright posts 6 by suitable fastening members 7. Twisted strands of paper which have been impregnated with a waterproofing compound and a fungicide, are woven warp and weft-wise, as indicated at 8 and 9, respectively, to provide an open mesh fencing. Selavage

2

portions 10 at the top and bottom of the open mesh fencing are formed by crowding a plurality of the warp strands together during the weaving operation and by incorporating in the weave of the selavage portion a reinforcing wire 11 at the time of weaving. In Figs. 2, 4 and 5, I have shown, in detail, one of the selavage portions 10 illustrating how the warp strands 8, interwoven with weft strands 9, are crowded to form a relatively close mesh. The reinforcing wire 11 is shown interwoven with the weft-wise strands 9 between two warp-wise strands 8.

The fencing 5, as previously indicated, is woven to generally provide an open mesh between the top and bottom selavage portions 10. Intermediate stiffened zones 12, are provided which extend in spaced parallel relation to the selavage portions. These stiffening zones are formed by crowding groups of the warp strands 8 closer together than in the remaining portion of the weave, as shown in Figs. 3 and 6.

The woven mesh fencing is made up in any desired length which is usually done up in rolls for storage and transportation. To install a snow fence of this kind, a row of posts 6 are first set up in suitable spaced relation. The height of the posts above the ground will be governed by the width of the fencing. The normal width of such fencing is 4 feet but this may be varied to meet specific requirements. The posts are preferably provided with side openings 1a adjacent the top and bottom. The outer end of a roll of fencing is then secured at the selavage portions 10 by fastening elements 7 to the top and bottom of the first post. Fastening elements 7 preferably comprise strands of twisted paper treated with a waterproofing and fungicidal compound but may be of cord or wire strands. The strands 7 are trained through a plurality of the weft strands 9 in the selavage portion 10 so as to provide a loop or bight across a plurality of the warp strands 8. The free ends of elements 7 are then fastened about the post with one end projecting through openings 1a in the post to hold the fencing, top and bottom, against sliding movement on the post. The intermediate stiffening zones 12 also have fastening elements 7 similarly trained through portions of the closely spaced warps and wefts, said elements being tied around the post to hold the intermediate portions of the fence to the posts at the stiffening zone. The post may be provided with additional openings similar to the openings 1a intermediate the top and bottom through which one strand of the fastening elements 7 at the intermediate stiffening zones 12 may be trained be-

fore said fastening elements are secured to the posts. As the fencing is unrolled it is similarly secured to each successive post in the row in the manner above described.

It will be appreciated that the woven wire 11 serves as a reinforcement to the stiffened selvage portions to prevent sagging and curling of the fencing between posts. The intermediate stiffening zones 12 have their warps sufficiently crowded together to ensure that the loop of the fastening element 7a will overlie portions of the warps and grip same without distorting the fencing. These stiffening zones also serve to stiffen the fence throughout its length along spaced narrow zones paralleling the upper and lower edges of the fence.

Although I have shown the stiffened zones extending parallel to the selvage portions, the stiffened zones may also be arranged to extend between the selvage portions and at right angles thereto. This would be accomplished by crowding groups of the weft strands together. With this modified form care would have to be exercised in spacing the fence posts to ensure that the fence would be secured to the post at the stiffened zones.

I claim:

1. A fencing strip formed of twisted strands of paper including warp and weft strands woven together to provide an open mesh paper fence, said fencing strip having stiffened selvage portions formed by crowding a plurality of the warp strands together and warp-wise reinforcing wire

strands interwoven in the warp-wise direction of said selvage portions.

2. A fencing strip as set forth in claim 1 in which said fencing strip is provided with spaced apart parallel stiffened zones intermediate and spaced from the stiffened selvage portions, each of said zones comprising groups of parallel warp strands crowded together more closely than in the remaining portion of the weave.

10 GEORGE LIONEL RODOLPHE LONGTIN.
